UNITED STATES PATENT OFFICE.

BENJAMIN J. MULLEN, OF LEETONIA, OHIO.

GAS-WASHER.

No. 805,929.

Specification of Letters Patent.

Patented Nov. 28, 1905.

Application filed March 8, 1905. Serial No. 248,983.

To all whom it may concern:

Be it known that I, BENJAMIN J. MULLEN, a citizen of the United States, residing at Leetonia, in the county of Columbiana and State of Ohio, have invented certain new and useful Improvements in Gas-Washers; and I do hereby declare the following to be a full, clear, and exact description of the invention, such as will enable others skilled in the art to which it appertains to make and use the same.

This invention relates to gas-washers for use in connection with blast-furnaces; and it consists in the novel construction and combination of the parts hereinafter fully described and claimed.

In the drawings, Figure 1 is a side view of a gas-washer, partly in section. Fig. 2 is a partial sectional plan view of the gas-washer. Fig. 3 is a detail vertical section of one of the gas-tubes drawn to a larger scale. Fig. 4 is a plan view of the gas-tube from below.

A is the vessel in which the washing of the gas is effected. The lower part of this vessel contains water which is maintained at a pre-arranged level by any approved means, and a plug b or other suitable means is provided for letting out the dirt and water from the said vessel whenever desired.

B is the inlet-pipe for gas from the blast-furnace, and C is the outlet-pipe for the washed gas. The vessel A is of any approved form, and the inlet and outlet pipes are connected to it in any convenient positions. D

is a gas-chamber inside the vessel A, with which the said inlet-pipe communicates, and d is a head in the said gas-chamber, which is arranged above the level of the water in the vessel A. A series of small chambers or pipes

E are supported from the head d, so that the gas is divided up into small volumes before it impinges upon the surface of the water. These pipes or chambers are connected to the head in any approved manner, and each pipe preferably has a collar e at its top, which engages with a recess in the head. In order to bring each small volume of gas in contact with the water separately and to prevent the gas issuing from one pipe from interfering with the

washing of the gas issuing from any other pipe, each pipe, or as many pipes as desirable, is provided with a cap F at its lower end. This cap communicates with the pipe to which it pertains and is larger in area than

the said pipe and has its bottom edge arranged, preferably, a little below the level of the water in the vessel A, so as to form a water seal. Each cap F is provided with one or more gas-escape holes f, arranged out of line with the pipe which supports the cap, and a series of these holes f is preferably provided around the top part of the cap above the level of the bottom of the pipe. Each cap may be formed integral with its pipe, if desired, or it may be connected with it in any approved manner.

G represents projections on the lower part of the pipe, and g represents projections on the cap. The cap may consist simply of a short ring or cylinder arranged, as shown. The cap is slid over the end of the pipe and is then partially revolved, so that the projections on the cap come over the projections of the pipe. The caps form enlargements at the bottoms of the pipes, and they may be connected to the said pipes in any other convenient manner besides that hereinbefore described.

What I claim is—

1. In a gas-washer, the combination, with a vessel for holding water at a prearranged level provided with an inlet-gas chamber and a head, of small chambers or pipes connected with the said gas-chamber, each said small chamber or pipe being provided with an enlargement at its lower part which has an outlet arranged above the water-level and out of line with the said small chamber or pipe.

2. In a gas-washer, the combination, with a vessel for holding water at a prearranged level provided with a gas-inlet chamber and a head, of pipes depending from the said head and provided at their lower ends with enlargements having gas-outlet openings arranged above the water-level and above the level of the bottoms of the said pipes.

3. In a gas-washer, the combination, with a vessel for holding water at a prearranged level provided with a gas-inlet chamber and a head, of pipes depending from the said head, and caps secured to the lower ends of the said pipes and provided with gas-outlet openings at their tops around the said pipes, said outlet-openings being arranged above the water-level and constantly communicating with the main outlet from the said vessel.

4. In a gas-washer, the combination, with a vessel for holding water provided with a

gas-inlet chamber and a head, of pipes depending from the said head and provided with projections at their lower ends, and caps which are slidable on the said pipes and which are provided with projections which rest on the aforesaid projections and outlet-holes for gas between the said projections.

In testimony whereof I have affixed my signature in the presence of two witnesses.

BENJAMIN J. MULLEN.
